STEADIER FOR ELONGATED WORKPIECES
AND MANDREL BARS

Heber C. Inslee, East Orange, N. J., assignor, by
mesne assignments, to Rockrite Processes, Inc.,
Stamford, Conn., a corporation of Delaware

Application January 28, 1944, Serial No. 520,022

11 Claims. (Cl. 80—14)

This invention relates to retractable steadiers for elongated workpieces and mandrel bars. The invention has been made especially with the idea of providing tube and mandrel bar steadyng and supporting means for a step-by-step tube reducing mill of the pilger type in which the tubes are reciprocated by a reciprocating member which grips the rear end of the tube and is given a slow forward movement to feed the tube to the dies and is returned to starting position for the positioning of a new tube, and in which the mandrel is carried by a long mandrel bar which is reciprocated but not fed forward; but steadiers according to the invention are adaptable for and may be used in other tube reducing mills and in mills for reducing solid bars or rods where it is required that the steadiers for the bar or rod be moved into and out of operative position.

The present invention is based on the invention described and claimed in my application Serial No. 501,104, filed September 3, 1943, now Patent Number 2,374,939, granted May 1, 1945, and certain features of invention of the steadier construction and controlling means shown herein are claimed broadly in said application. Said application shows a duplex tube reducing mill in which the tubes are reciprocated by members which grip the rear ends of the tubes and which are mounted and reciprocated in a longitudinally movable tube unit housing which is given a slow forward movement to feed the tubes to the reducing rolls and is returned to starting position with a quick backward movement for the positioning of new tubes, and in which the mandrels are carried by long mandrel bars which are reciprocated but are not fed forward, and shows tube steadiers and mandrel bar steadiers which are moved into and out of operative position and are operated to close about the tube or mandrel bar after being moved into operative position and to open before being withdrawn from operative position, and means whereby, as the tube unit housing is fed forward, the tube steadiers, in order to avoid interference with the forwardly moving housing, are withdrawn after being first opened, and whereby the mandrel bar steadiers are moved into operative position and then closed about the mandrel bars during the forward movement of the tube unit housing and are opened and withdrawn during the quick backward movement of the housing in time to avoid interference with the housing, and whereby the tube steadiers may be positioned and closed after the new tubes have been placed in position.

In the apparatus shown in said application,

the carriers for the tube and mandrel bar steadiers are mounted above the pass lines of the tubes and mandrel bars and are operated to move the steadiers downward to their operative positions and to withdraw them by moving them upward. The steadiers of the present invention have been designed especially for a single tube reducing mill of the kind referred to, and for greater convenience in introducing and positioning the new tubes in the mill, the carriers for the steadiers are arranged to move horizontally from one side of the mill; and the invention includes improved operating mechanism for the steadiers, and operating and control means for advancing and retracting the carriers and for closing and opening the steadiers, each steadier unit having an air cylinder, or other suitable motor means, for moving the carrier and an air cylinder, or other suitable motor means, for closing and opening the steadier, and control means whereby, when the carrier, advanced by its air cylinder, has moved the steadier to operative position, air is admitted to the steadier air cylinder to cause the steadier to be closed, and whereby, when the steadier has been opened by its air cylinder, air is admitted to the carrier air cylinder to cause the carrier to be retracted to withdraw the steadier. The new steadier mechanism and operating and control means, although designed especially for horizontally moving carriers, are not to be limited thereto.

A full understanding of the invention can best be given by a detailed description of an embodiment of the various features of the invention in the form now considered best as applied to a reducing mill of the kind referred to, and such a description will now be given in connection with the accompanying drawings, in which:

Fig. 1 is a plan view of a tube reducing mill embodying the invention;

Fig. 2 is a side elevation of the mill;

Fig. 3 is a plan view on a larger scale of one of the steadier units;

Fig. 4 is a side view on the same scale of one of the steadier units;

Fig. 5 is a view on a still larger scale of the inner end of one of the steadiers looking from the left of Figs. 3 and 4;

Fig. 6 is a view on the same scale as Fig. 5 of the outer end of one of the steadier units looking from the right of Figs. 3 and 4;

Fig. 7 is a view partly in section of one of the double solenoid operated air valve devices; and

Fig. 8 is a diagrammatic view illustrating means for controlling the operation of the air cylinders of the steadier units.

The tube reducing mill shown by Figs. 1 and 2 of the drawings is the single mill of my application Serial No. 510,879, filed November 19, 1943. It is similar in its operating parts other than its tube and mandrel bar steadiers and its reciprocating driving mechanism to the duplex tube reducing mill of my application Serial No. 442,769, filed May 13, 1942. Figs. 1 and 2 of my said application Serial No. 510,879. The reciprocating driving mechanism partly shown on a small scale in said figures is fully illustrated and described and claimed in said application Serial No. 510,879.

Referring to the drawings, and first to Figs. 1 and 2, the mill shown comprises a roll stand 10, a mandrel reciprocating and turning unit 11, a tube reciprocating, turning and feeding unit 12, tube feeding mechanism 13, tube and mandrel reciprocating driving mechanism 14, and an exit tube reciprocating and turning unit 15.

The roll stand comprises a pair of overhung gapped working or die rolls 20 fast on the ends of shafts journaled in chocks in a massive frame or housing 22. A pair of overhung stress-balancing rolls 24 (one of which shows in Fig. 1) of the same diameter as the die rolls are fast on the roll shafts at the opposite side of the housing from the die rolls, and there is an overhung backing roll 26 for each of the die rolls and for each of the stress-balancing rolls. At the entrance side of the housing there is a clamping device 27 which is open during operation of the mill and is closed to clamp the rear end of a partially reduced tube when the mill is stopped.

The operating parts of the mandrel reciprocating and turning unit 11 are mounted in a stationary housing 30 seated on the rear end of a longitudinally extending base 31. These operating parts are driven by a transverse driving shaft 32 which is oscillated by the reciprocating mechanism 14. A lever arm 33 fast on shaft 32 reciprocates the mandrel bar 40, which has at its forward end a tapered mandrel. The mandrel bar extends through and is detachably secured by means of a clamp 41 to a longitudinally reciprocable and axially rotatable sleeve 42 the forward end of which is rotatably connected to a sliding member 43 which is reciprocated by the arm 33 through a link 44.

A longitudinal rock shaft 50 which extends forward from one side of the mandrel unit housing 30 is oscillated by the drive shaft 32 through a bevel segment gear 52 on the drive shaft meshing with a bevel pinion 53 on shaft 50.

The tube reciprocating, turning and feeding unit 12 comprises a housing 60 mounted to slide on the base 31 between the position shown by full lines in Figs. 1 and 2 and that indicated by dotted lines in Fig. 2. The rear end of the tube T is detachably secured by a clamp 61 to the forward end of a longitudinally reciprocable and axially rotatable sleeve 62 through which the mandrel bar extends. The rearward end of sleeve 62 is connected to a sliding member 63 which is connected by a link 64 to a lever arm 65 extending from a pivotally mounted hub 66. This hub carries also a bevel gear segment 67 which meshes with a bevel pinion 68 carried by a sleeve which is slidable on the shaft 50 and is splined thereto so as to be turned therewith, and which is also mounted in a bearing 69 on the housing 60 by which it is held against movement longitudinally with respect to the housing. By oscillation of the shaft 50, therefore, the arm

65 is oscillated and the sleeve 62 and the tube secured thereto are reciprocated. The lever arm 65 of the tube unit and the lever arm 33 of the mandrel unit have the same angular motion and are of the same effective radial length and are driven in unison, so that the tube and mandrel are given equal and synchronous reciprocations.

During each non-working forward stroke of the tube and mandrel, the tube unit housing 60 is given a short forward feeding movement by which the tube is given an increment of feed with relation to the mandrel. This step-by-step forward feeding of the tube unit is effected by a pinion 70 driven, through a one-way clutch of the tube feeding mechanism 13, from a shaft 71, the pinion meshing with a rack 72 extending backward from the tube unit housing through a guide opening in the stationary housing 30 of the mandrel unit. The pinion and rack serve also for giving a quick backward movement to the tube unit when, after being disconnected from a nearly completed tube, it is to be moved back for the positioning of a new tube, the pinion being then disconnected from the one-way feeding clutch and being driven by a motor 75 which is under push button control. The shaft 71 is oscillated by the drive shaft 32 through a bevel segment gear 73 on the drive shaft which meshes with a bevel pinion 74 on shaft 72.

As the reduced portion of the tube advances beyond the die rolls it is engaged by a friction clamp 80 of the exit tube reciprocating and turning unit 15. This friction clamp permits slippage under the increment of feed of the new tube during each non-working stroke and slippage during the working stroke due to the elongation of the tube. The exit tube unit 15 comprises a stationary housing 81 in which is mounted a longitudinally reciprocable and axially rotatable sleeve 82 which carries the friction clamp 80 and which is reciprocated in unison with the sleeve 62 of the main tube unit by means of an oscillating lever arm 83 connected by a link 84 to a sliding member 85 connected to the sleeve. The hub of the lever arm 83 carries a bevel gear segment 86 which meshes with a bevel pinion 87 fast on a shaft 88 which is connected with and oscillated by the rock shaft 50. Lever arm 83 has the same angular movement and is of the same effective radial length as the lever arms 65 and 33 and is driven in unison therewith.

In the operation of the mill, after each working stroke of the tube and mandrel, during which a length of the tube is pressed between working portions of the grooves of the die rolls, the tube is released by the die rolls and the tube and mandrel then make a forward return stroke during which they are given a partial turn and the tube unit housing 60 is moved forward to give an increment of feed to the tube. When the housing 60 has been advanced to its extreme forward position, as shown in Fig. 1 and by full lines in Fig. 2, the mill is stopped and the unreduced rear end of the tube is clamped by the clamp 27. The sleeve 62 of the tube unit is then disconnected from the tube and the mandrel bar, is disconnected from the sleeve 42, and the housing 60 is moved backward to its extreme retracted position indicated by dotted lines in Fig. 2, and the mandrel bar is drawn back, by suitable means not shown, until the forward end of the mandrel is back of the tube clamp of the retracted tube unit. A new tube may be brought into position in the mill and its rear end secured by the clamp 61, and when the mandrel bar has been returned

to operative position and connected to sleeve 42 the mill may again be started in operation.

The mill as so far described is more fully shown and described in my said application Serial No. 442,769, with this principal difference, however, that the mill of said application is a duplex mill which operates on two tubes at the same time, having die rolls on each side of the roll stand housing instead of die rolls on one side and stress-balancing rolls on the other side as herein shown, and having two longitudinal rock shafts like the shaft 50, one on each side of the base 31, and tube and mandrel gripping and operating parts on each side of the mandrel unit and tube unit housings.

The mill as shown has one tube steadier device, or unit, and one mandrel bar steadier unit. This has so far been found sufficient, but the invention is not to be limited to the provision of only one tube steadier unit and one mandrel bar steadier unit. Each steadier unit 100 comprises a bed frame 101 which is secured to and extends outward horizontally from the base 31 on the side away from the mandrel and tube reciprocating members, and the steadier units are positioned lengthwise of the mill so that the tube may be steadied and supported at a point about midway between the roll stand and the forward end of the tube unit housing when the housing is in its rearmost position, but preferably somewhat nearer to the roll stand, and that the mandrel bar may be steadied and supported at a point about midway between the forward end of the mandrel unit housing and the rear end of the tube unit housing when the latter is in its forwardmost position.

The tube steadier unit and the mandrel bar steadier unit may be, and most desirably are, of the same construction, except that the tube and mandrel bar engaging members, the steadiers proper, 110, are of different size to suit the size of the tube and mandrel bar, respectively. Figs. 3, 4, 5 and 6 illustrate a mandrel bar steadier unit of preferred construction for a mill such as shown by Figs. 1 and 2.

This steadier unit has an elongated carrier 111 mounted to slide on horizontal slideways 112 on the bed frame 101 and on the top of the longitudinal members 113 of the mill base 31 to move its steadier 110 into operative position and to withdraw it out of the path of movement of the tube unit housing 60. The carrier is given its forward or positioning movement and its withdrawing movement by a double acting air cylinder 115 mounted in horizontal position on the frame 101. As shown, the outer or rear end portion of the carrier is formed to straddle the air cylinder, and the end of the piston rod 116 of the air cylinder is secured to a cross piece 117 extending between the side walls of the carrier. Forward movement of the carrier is limited by a movement limiting bar 118 extending through an opening in a stop plate 119 on the carrier and anchored at its outer or rear end to a bracket 120 extending upward from the outer end of frame 101. An adjustable stop piece 121 on the front end of bar 118 engages plate 119 to limit and determine the forward movement of the carrier. At the end of its backward movement the carrier is stopped by engagement of its stop plate 119 with a buffer block 122 of rubber or other suitable material on the bracket 120.

The side walls of the carrier extend forward from the cross piece 117 and have at their front

ends upwardly extending portions 123 which are connected by a cross piece 124.

The steadier 110 is formed by two jaws 125 and 126 which are pivotally mounted on a pivot pin 127 carried by and extending between the upper ends of the side wall extensions 123. Extending from the hub of jaw 125 is a short arm 128 which is connected by an adjustable link 129 to the free end of a lever 130 the other end of which is fast on a shaft 131 mounted to rock in bearing bosses on the side walls of the carrier; and a short arm 132 extending from the hub of the jaw 126 is also connected by an adjustable link 133 to the free end of lever 130. The two links are connected to the lever 130 at opposite sides thereof by means of pivot pin 134 extending through the lever end.

By upward movement of lever 130, the two jaws of the steadier are turned on their pivot upward and toward each other to close about the mandrel bar, as shown by full lines in Figs. 3 and 4, and by downward movement of the lever the steadier is opened, the jaws being turned outward to the position shown by dotted lines in Fig. 4. After the steadier and its operating parts have been moved inward by the carrier 111 to the position shown in Figs. 3 and 4, lever 130 is moved downward to close the steadier, and before the steadier and its operating parts are withdrawn by outward backward movement of the carrier, the lever is moved upward to open the steadier, all parts of the steadier jaws when in open position being below the mandrel bar.

Lever 130 is swung between its two positions shown by full lines and by dotted lines in Fig. 4 to close and open the steadier by a double acting air cylinder 140 which is pivotally mounted at its rear end on a pin 141 carried by a bracket 142 projecting upward from the carrier. The piston rod 143 of the air cylinder is connected to the knuckle joint of a toggle 144 one link of which is connected to lever 130, the other link being connected to a block 145 which seats on a shoulder 146 extending from the cross piece 124 and which is pressed toward its seat by a heavy cushion spring 147. Forward movement of piston rod 143 straightens the toggle to force the lever downward until, before the toggle is fully straightened, the steadier is fully closed and the lever has come to rest in engagement with a stop 148. The block 145 is then lifted slightly against the pressure of spring 147 as the piston rod continues its forward movement until stopped by engagement with the cross piece 124 after the toggle has been fully straightened and its knuckle then moved to a past-dead-center holding position as shown in Fig. 4. By backward movement of the piston rod 143, the toggle is broken and its knuckle moved backward to raise the lever to its upper position, thereby opening the steadier.

For holding the lever 130 in position after it has been raised by the backward movement of piston rod 143 and the air has been cut off from cylinder 140, counterweights 150 are provided, one on each side of the carrier 111, carried by lever arms 151 fast on the ends of shaft 131.

A downwardly projecting lug 155 on the lever 130 near its forward end serves to prevent backward movement of the carrier 111 by engagement with one of the longitudinal members 113 of the mill base when the lever 130 is in its down closed-steadier position. The carrier is thus locked in its forward position when the steadier is closed on the mandrel bar, being held against forward

movement by the bar 118 and against backward movement by the lug 155.

The air supply to air cylinder 115 through tubes 160 and 161 connected to the ends of the cylinder is controlled by a double two-position solenoid operated valve device 170 (see Fig. 7) by which when one of its solenoids is energized the tube 160 of air cylinder 115 is connected with the air supply (not shown) and the tube 161 is connected with the exhaust, to cause the carrier to be moved forward, and by which when its other solenoid is energized the tube 161 is connected with the air supply and tube 160 is connected with the exhaust to cause the carrier to be withdrawn, or by other suitable valve means. The air supply to air cylinder 140 through tubes 162 and 163 is similarly controlled by a double two-position solenoid operated valve device 171. The valve devices 170 and 171 are alike and are described in detail hereinafter.

The control valves of the two air cylinders of the tube steady unit are operated to cause the carrier to move its steady into operative position after a new tube has been positioned in the mill and to close the steady about the tube, and to open the steady and move the carrier to withdraw the steady during forward movement of the tube unit housing in time to avoid the steady being struck by the housing; and the control valves of the two air cylinders of the mandrel bar steady unit are operated to cause the carrier to move its steady into operative position and to close the steady about the mandrel bar during the forward movement of the tube unit housing when the housing has moved beyond them, and to open the steady and move the carrier to withdraw the steady during the backward movement of the tube unit housing in time to avoid the steady being struck by the housing.

Most desirably, the cycle of operations of the control valves of the mandrel bar steady unit for positioning and closing its steady, and the cycle of operations of the control valves of the mandrel bar steady unit for opening and withdrawing its steady, and the cycle of operations of the control valves of the tube steady unit for opening and withdrawing its steady, are initiated by means controlled by movement of the tube unit housing. The starting of the cycle of valve operations of the tube steady unit for positioning and closing its steady after a new tube has been positioned in the mill is most desirably under push-button or other manual control. When the cycle of operations of the control valves of any of the steady units has been started, the cycle is completed automatically by means responsive to movement of the piston rods of the air cylinders or of parts moved by the piston rods.

The double two-position solenoid-operated valve devices 170, 171, of which there are four, one for each of the air cylinders of each of the steady units, and which are designated respectively by the reference numerals 170a, 171a, 170b, and 171b in the diagrams of Fig. 8, are of known commercial form as shown more or less conventionally by Fig. 7, where one of these devices is shown for controlling the air supply to one of the air cylinders 115. The device shown has two slide valves 180 and 181, moved by pivoted levers 182 and 183 connected to solenoids 184 and 185 by which the levers are moved downward against the pressure of springs 186 and 187, which, when the solenoids are de-energized, swing the levers upward and hold them in their raised position. Pressure air is supplied, from a source not shown,

through a tube 190 to pressure chamber 191 from which a port 192 leads to the connecting port of valve 180 and a port 193 leads to the connecting port of valve 181. The valves are mounted in an exhaust chamber 194 from which there is an exhaust outlet 195 and ports 196 and 197 to which the tubes 160 and 161 are connected. When the solenoid 184 is energized, valve 180 is moved down to the position shown in Fig. 7, thereby shutting off port 196 from the exhaust chamber and connecting it through the valve port with port 192, thus connecting tube 160 with the air supply. Air will then be supplied to the air cylinder to move its piston rod outward. When solenoid 184 is deenergized, spring 186 swings lever 182 upward to move valve 180 up to the position corresponding to that of valve 181 in Fig. 7, thereby cutting off the air from tube 160 and opening port 196 to the exhaust chamber 194, whereby the air pressure in the air cylinder is relieved. Similarly, when solenoid 185 is energized, valve 181 is moved down to connect the ports 193 and 197 for supplying air through tube 161 to the air cylinder to move its piston rod inward; and when solenoid 185 is deenergized, valve 181 is moved up to the position shown in Fig. 7 to cut off the air from tube 161 and connect said tube with the exhaust.

The operation of the tube and mandrel bar steady units of the tube reducing mill illustrated during one forward and return movement of the tube unit housing will now be described in connection with the illustrative diagram, Fig. 8, in which A represents the mill with its tube unit housing 60 in its fully retracted position adjacent to the housing 30 of the mandrel unit, the die rolls 20 and the tube steady unit 100a and the mandrel bar steady unit 100b being indicated; B represents the air cylinders 115a and 140a and the air supply and exhaust connections and control valves 170a and 171a of the tube steady unit; and C represents the air cylinders 115b and 140b and the air supply and exhaust connections and control valves 170b and 171b of the mandrel steady unit. In this illustrative diagram the electrical wiring is intentionally left out. The required wiring connections between the various switches and the solenoid valves can be readily supplied by any qualified electrical engineer, and to make a complete wiring diagram would require the showing of a great amount of wiring making a very complicated diagram, and the specification would be needlessly lengthened without more clearly disclosing the invention.

A new tube having been positioned in the mill and its rear end secured to the tube reciprocating sleeve of the tube unit, before the mill is started in operation the solenoid valve 170a of the tube steady unit is operated by push-button *d* to cause air cylinder 115a to move the carrier and tube steady forward. At the end of the forward stroke of the piston rod of cylinder 115a, limit switch *e* operates solenoid valve 170a to cut off the air from cylinder 115a, and operates solenoid valve 171a to cause air cylinder 140a to move its piston rod forward and thereby close the tube steady about the tube. At the end of the forward stroke of the piston rod of cylinder 140a, limit switch *f* operates valve 171a to cut off the air from cylinder 140a. The mill being then set in operation, the tube unit housing starts on its forward feeding movement toward the die rolls.

Before the tube unit housing reaches the tube steady unit 100a, a tripper *g* on the housing trips switch *h*, thereby operating solenoid valve

171a to cause air cylinder 140a to retract its piston rod and thereby open the tube steadier. At the end of the inward stroke of the piston rod of cylinder 140a, limit switch i operates valve 171a to cut off the air from cylinder 140a and operates valve 170a to cause air cylinder 115a to retract its piston rod and thereby withdraw the carrier and tube steadier. At the end of the inward stroke of the piston rod of cylinder 115a limit switch j operates valve 170a to cut off the air from cylinder 115a. Limit switch h when tripped by forward movement of the tube unit housing also operates solenoid valve 170b of the mandrel bar steadier unit to cause air cylinder 115b to move the carrier and mandrel bar steadier forward. At the end of the forward stroke of the piston rod of cylinder 115b, limit switch k operates valve 170b to cut off the air from cylinder 115b and operates solenoid valve 171b to cause air cylinder 140b to move its piston rod forward and thereby close the mandrel bar steadier about the mandrel bar. At the end of the forward stroke of piston rod of cylinder 140b, limit switch l operates valve 171b to cut off the air from cylinder 140b.

Before the tube unit housing reaches the mandrel rod steadier unit on its return movement, a tripper m on the housing trips switch n which operates valve 171b to cause air cylinder 140b to retract its piston rod and thereby open the mandrel bar steadier. Tripper m and switch n are offset laterally from tripper g and h. At the end of the inward stroke of the piston rod of cylinder 140b, limit switch o operates valve 171b to cut off the air from cylinder 140b, and also operates valve 170b to cause air cylinder 115b to retract its piston rod and thereby withdraw the carrier and mandrel bar steadier; and at the end of the inward stroke of the piston rod of cylinder 115b limit switch p operates valve 170b to cut off the air from cylinder 115b. The carriers of both steadier units are thus retracted when the tube unit housing completes its backward movement to the position shown in A.

What is claimed is:

1. A steadier unit, comprising a carrier, a steadier carried by said carrier and adapted to be closed and opened, motor means for moving the carrier inward to move the steadier into operative position and for moving the carrier outward to withdraw the steadier, motor means on the carrier for closing and opening the steadier, controlling means for causing the carrier motor means to move the carrier inward, automatically operated controlling means for causing the steadier motor means to close the steadier when it has been positioned, controlling means for causing the steadier motor means to open the steadier, and automatically operated controlling means for causing the carrier motor means to move the carrier outward to withdraw the steadier when it has been opened.

2. A steadier unit, comprising a carrier, a steadier carried by said carrier and adapted to be closed and opened, motor means for moving the carrier inward to move the steadier into operative position and for moving the carrier outward to withdraw the steadier, motor means on the carrier for closing and opening the steadier, controlling means for causing the carrier motor means to move the carrier inward, automatically operated controlling means for causing the steadier motor means to close the steadier when it has been positioned, controlling

means for causing the steadier motor means to open the steadier, automatically operated controlling means for causing the carrier motor means to move the carrier outward to withdraw the steadier when it has been opened, and means locking the carrier against movement when the steadier is closed.

3. A steadier unit, comprising a carrier, a steadier carried by said carrier and adapted to be closed and opened, motor means for moving the carrier inward to move the steadier into operative position and for moving the carrier outward to withdraw the steadier, motor means on the carrier for closing and opening the steadier, controlling means for causing the carrier motor means to move the carrier inward, means controlled by movement of a part moved by the carrier motor means for causing the steadier motor means to close the steadier when it has been positioned, controlling means for causing the steadier motor means to open the steadier, and means controlled by movement of a part moved by the steadier motor means for causing the carrier motor means to move the carrier outward to withdraw the steadier when it has been opened.

4. A steadier unit, comprising a bed having a slideway, a carrier mounted on said slideway, a steadier carried by said carrier and adapted to be closed and opened, an air cylinder for moving the carrier inward to move the steadier into operative position and for moving the carrier outward to withdraw the steadier, an air cylinder on the carrier for closing and opening the steadier, means for causing air to be supplied to the carrier air cylinder to move the carrier inward, means controlled by movement of a part moved by the carrier air cylinder for causing air to be supplied to the steadier air cylinder to close the steadier when it has been positioned, means for causing air to be supplied to the steadier air cylinder to open the steadier, and means controlled by movement of a part moved by the steadier air cylinder for causing air to be supplied to the carrier air cylinder to move the carrier outward to withdraw the steadier when it has been opened.

5. A steadier unit, comprising a steadier movable into and out of operative position and adapted to be closed and opened, motor means for moving the steadier into operative position and for withdrawing it, motor means for closing and opening the steadier, controlling means for causing the first said motor means to move the steadier into operative position, means controlled by movement of a part moved by the first said motor means for causing the second said motor means to close the steadier when it has been positioned, controlling means for causing the second said motor means to open the steadier, and means controlled by movement of a part moved by the second said motor means to cause the first said motor means to withdraw the steadier when it has been opened.

6. A steadier unit, comprising a carrier, a steadier carried by the carrier formed of two jaw members movable toward and from each other, motor means for moving the carrier inward to move the steadier into operative position and for moving the carrier outward to withdraw the steadier, motor means for closing and opening the steadier jaw members mounted on the carrier, means for limiting the inward movement of the carrier, and a stop member on a part moved by the steadier motor means for prevent-

ing outward movement of the carrier when the steadier is closed.

7. In a reducing mill having a pair of reducing members, and a feeding member for engaging the rear end of an elongated workpiece, and means for moving said feeding member forward to feed the workpiece to the reducing members and for withdrawing the feeding member for the placing of a new workpiece: a workpiece steadier movable into and out of operative position and adapted to be closed and opened, motor means for moving the steadier into operative position and for withdrawing it out of the path of movement of said feeding member, and motor means for closing and opening the steadier, means controlled by movement of the feeding member during its forward movement for causing the second said motor means to open the steadier, and means controlled by movement of a part moved by the second said motor means for causing the first said motor means to withdraw the steadier when it has been opened.

8. In a reducing mill having a pair of reducing members, and a feeding member for engaging the rear end of an elongated workpiece, and means for moving said feeding member forward to feed the workpiece to the reducing members and for withdrawing the feeding member for the placing of a new workpiece: a slideway extending laterally from one side of the mill, a carrier on said slideway, a workpiece steadier carried by said carrier adapted to be closed and opened, motor means for moving the carrier inward to move the steadier into operative position beneath the workpiece and for moving the carrier outward to withdraw the steadier, motor means on the carrier for closing and opening the steadier, controlling means for causing the carrier motor means to move the carrier inward to position the steadier, means controlled by movement of a part moved by the carrier motor means for causing the steadier motor means to close the steadier when it has been positioned, means controlled by movement of said feeding member for causing the steadier motor means to open the steadier during the forward movement of the feeding member, and means controlled by movement of a part moved by the steadier motor means for causing the carrier motor means to move the carrier outward to withdraw the steadier when it has been opened.

9. In a reducing mill having a pair of reducing members, and a feeding member for engaging the rear end of an elongated workpiece, and means for moving said feeding member forward to feed the workpiece to the reducing members and for withdrawing the feeding member for the placing of a new workpiece: a workpiece steadier movable into and out of operative position and adapted to be closed and opened, motor means for moving the steadier into operative position and for withdrawing it out of the path of movement of said feeding member, motor means for closing and opening the steadier, controlling means for causing the first said motor means to move the steadier into position, means controlled by movement of a part moved by the first said motor means for causing the second said motor means to close the steadier when it has been positioned, means controlled by movement of said feeding member for causing the second said motor means to open the steadier during the forward movement of the feeding member, and means controlled by movement of a part moved by the second said motor means to cause the first said mo-

tor means to withdraw the steadier when it has been opened.

10. In a tube reducing mill having a pair of reducing dies, and a mandrel carried by a mandrel bar, and a tube feeding member for engaging the rear end of the tube, and means for moving the tube feeding member forward to feed the tube to the reducing dies and for withdrawing said member for the placing of a new tube: a mandrel bar steadier movable into and out of operative position and adapted to be closed and opened, motor means for moving the steadier into operative position and for withdrawing it out of the path of the tube feeding member, motor means for closing and opening the steadier, means controlled by movement of the tube feeding member during its forward movement for causing the first said motor means to move the steadier into position, means controlled by movement of a part moved by the first said motor means for causing the second said motor means to close the steadier when it has been positioned, means controlled by movement of the tube feeding member during its backward movement for causing the second said motor means to open the steadier, and means controlled by movement of a part moved by the second said motor means for causing the first said motor means to withdraw the steadier when it has been opened.

11. In a tube reducing mill having a pair of reducing dies, and a mandrel carried by a mandrel bar, and a tube feeding member for engaging the rear end of the tube, and means for moving the tube feeding member forward to feed the tube to the reducing dies and for withdrawing said member for the placing of a new tube: a tube steadier unit and a mandrel bar steadier unit, each comprising a carrier and a steadier carried by the carrier adapted to be closed and opened and motor means for moving the carrier inward to move the steadier into operative position and for moving the carrier outward to withdraw the steadier and motor means on the carrier for closing and opening the steadier; controlling means for the tube steadier unit comprising means for causing the carrier motor means to move its carrier inward to position the steadier, means controlled by movement of a part moved by the carrier motor means for causing the steadier motor means to close the steadier when it has been positioned, means controlled by movement of said tube feeding member during its forward movement for causing the steadier motor means to open the steadier, means controlled by movement of a part moved by the steadier motor means for causing carrier motor means to move the carrier outward to withdraw the steadier when it has been opened; and controlling means for the mandrel bar steadier unit comprising means controlled by movement of said tube feeding member during its forward movement for causing the carrier motor means to move its carrier inward to position the steadier, means controlled by movement of a part moved by the carrier motor means for causing the steadier motor means to close the steadier when it has been positioned, means controlled by movement of the tube feeding member during its backward movement for causing the steadier motor means to open the steadier, and means controlled by movement of a part moved by the steadier motor means for causing the carrier motor means to move the carrier outward to withdraw the steadier when it has been opened.
